UNITED STATES PATENT OFFICE.

FREDERICK WHITTLESEY MCKOWN, OF NEW YORK, N. Y., ASSIGNOR TO WESTERN ELECTRIC COMPANY, INCORPORATED, OF NEW YORK, N. Y., A CORPORATION OF NEW YORK.

TELEPHONE TRANSMISSION.

Application filed September 28, 1921. Serial No. 503,755.

This invention relates to telephone transmission.

Experiments have shown that the voice frequency range can be divided into parts 5 each of which will give a commercial degree of articulation. One object of the invention is to utilize the principle involved in this discovery for satisfactorily repeating voice currents in opposite directions in a line without regard to conditions of impedance unbalance in the line. Another object of the invention is to utilize this principle to enable a plurality of pairs of subscribers to talk over the same pair of lines 10 simultaneously.

The first of these objects is accomplished by transmitting only a part of the voice frequency range in one direction and transmitting the remainder, or a part of the remainder, in the opposite direction, each of 15 these parts being sufficient to represent intelligible speech. This method makes it possible to employ frequency separation of the oppositely directed transmissions at the repeaters, so that the gain of the repeaters is limited not by considerations of line impedance or impedance unbalance, but only by the efficiency of the filters or other means used to effect the frequency separation, and furthermore, the necessity for the balancing networks ordinarily employed in other systems is avoided.

To accomplish the second object stated above one duplex conversation is limited to 20 an intelligible part only of the voice frequency range, transmission in both directions over a line using this part of the range, and the remainder of the range, or a part of the remainder, is used to transmit over the same line a second duplex conversation. Frequency selective means, preferably filters, are employed to limit the frequencies transmitted between the line and each subscriber to the part of the frequency 25 range assigned to the pair of subscribers including that subscriber.

Further objects of the invention will be apparent from the following detailed description and the appended claims taken in connection with the accompanying drawings wherein Fig. 1 is a diagram of a repeating system employing entirely distinct repeat-

ing channels for oppositely directed transmissions, with amplifying elements individual to the two channels; Fig. 2 is a 55 diagram of a modified repeating system using an amplifying element arranged to serve both channels; Fig. 3 is a diagram similar to that of Fig. 2, but with filters connected in parallel rather than in series 60 as in Fig. 2; and Fig. 4 is a diagram of a multiplex telephone system.

In Fig. 1 a line W and a line E are connected by a repeater station S comprising filters FE and FW and amplifiers or repeaters RE and RW. Supposing a voice current containing all of the usual frequencies of the voice range to approach station S from line W, at the station S it enters the output of amplifier RW and the input of filter FE. The energy absorbed in the output of the amplifier RW is of course lost. Approximately one half of the frequencies are suppressed in filter FE, which may be of any suitable type, but the other half 70 reaches the input of amplifier RE and are amplified thereby. The amplified current goes onto the line E after passing through the impedance looking into the input end of filter FW, which may be of any suitable type 75 and should be designed, as for instance in a way indicated hereinafter, to be comparatively low for these frequencies. The filter FW is designed to suppress these frequencies to prevent them from reaching the repeater RW. The current reaching line E then only contains a part of the frequencies which left line W, but the received frequencies are sufficient for satisfactory transmission of speech.

The operation of transmitting from line E to line W is of course the same except that the transmission is through filter FW and amplifier RW and the filter FW passes only those frequencies which are not passed by filter FE.

Various distributions of frequency bands may be employed. For instance, the filter FE may be designed to suppress all voice frequencies above 1500 cycles per second, 100 and the filter FW to suppress all voice frequencies below 1500 cycles or vice versa. Or one of the filters may suppress from 500 to 900 cycles and all voice frequencies above

2000 cycles while the other filter is designed to suppress from 0 to 500 cycles and from 900 to 2000 cycles. Or one of the filters may suppress from 300 to 600 cycles, and from 1100 to 1600 cycles and all voice frequencies above 2700 cycles while the other filter suppresses from 0 to 300 cycles, and from 600 to 1100 cycles and from 1600 to 2700 cycles.

Tests indicate that the articulation is materially increased when the more elaborate complementary filters are used instead of merely a high pass filter and a low pass filter. The number of frequency bands to be used in each group, or in each channel, is limited at the lower side by the required degree of naturalness and articulation and at the upper side by the fact that more bands require more complicated filters and cause increased losses, due to the overlapping of the attenuation bands of the filters in one channel with the attenuation bands of the filters in the other channel.

The repeater circuit of this invention requires no impedance balance, and permits of greater transmission gains than do circuits in which the gain is limited by considerations of impedance unbalance. The system is not affected by any irregularities in line impedance. An important field of application of the invention is in its use in a cord circuit repeater between trunks having irregular impedance characteristics or in an emergency cord circuit repeater in an exchange for connecting trunks in which temporary impedance irregularities have been introduced accidentally. Another important field of application of the invention is in its use in connecting trunks which are not intended for repeater operation, over which it is at times desirable to give repeater service. Still another important field of application of the invention is in its use in repeating in long temporary lines, as for instance in Army work. The permissible gain in volume of transmission obtainable in any case depends upon the minimum attenuation of the filter FW or FE for the frequencies passed by the filter FE or the filter FW, respectively.

If desired the impedances looking into the West ends of the two separate channels at the repeater station S in Fig. 1 can be connected to line W in parallel with each other rather than in series. Similarly, the impedances of the two channels, looking into their East ends, may be connected in parallel. Further, if desired a part of the filter in each channel can be placed at each side of the amplifier in that channel, the filters having been shown wholly on the input side of the amplifiers for the reason that there is then less tendency to overloading of the amplifiers.

Fig. 2 shows a circuit arrangement whereby both channels at the repeater station are served by the same amplifier, designated R.

Filters 1 and 2 are alike, and each may be of any of the types of filters which are intended to be represented by FE in Fig. 1. Filters 3 and 4 are alike, and each may be of any of the types of filters which are intended to be represented by FW in Fig. 1. The filters 1 and 2 may transmit any part of the voice frequency range which any of the filters represented by FE in Fig. 1 may transmit, and the filters 3 and 4 may then transmit the remaining part of the voice frequency range.

In the operation of the system of Fig. 2, when a voice current containing all of the usual frequencies of the voice range is being transmitted East in line W, this current passes from line W through the impedance looking into the output of filter 4, and to the input of filter 1. Filter 1 passes only approximately one-half of these frequencies. Filter 4 passes the other half, but the energy of this other half is wasted in the impedance looking into the output of repeater R and the impedance looking into the input end of filter 2, since the repeater is unilateral current transmitting element and the filter 2 is designed to suppress this other half of the voice frequencies. The frequencies passed by filter 1 pass on through the impedance looking into the output end of filter 3, to the input of amplifier R, are amplified by the amplifier and are then passed through the impedance looking into the input end of filter 4, and through filter 2 and the impedance looking into the input end of filter 3, to line E. Filter 3 will not pass these frequencies. The impedances looking into the output end of filter 4, the output end of filter 3, the input end of filter 4 and the input end of filter 3 should be designed, as for instance in a way indicated hereinafter, to be low for these frequencies. The operation of transmitting from line E to line W is of course the same, except that the transmission is through filters 3 and 4 instead of through filters 1 and 2, and the filters 3 and 4 pass only those frequencies which are not passed by filters 1 and 2.

In Fig. 3 two oppositely directed channels for transmitting complementary frequency ranges are both served by the same amplifier R, as is the case in the system of Fig. 2. Each of the filters F_1 and F_1' of Fig. 3 transmits the same part of the voice frequency range that filters 1 and 2 of Fig. 2 transmit. Each of the filters F_2 and F_2' transmits the same part of the voice frequency range that filters 3 and 4 of Fig. 2 transmit.

In the operation of the system of Fig. 3, when a voice current containing all of the usual frequencies of the voice range is being transmitted East in line W, this current passes from line W to the input of filter F_1 , and the output of filter F_1' in parallel.

Filter F_1 passes only approximately one half of these frequencies. Filter F'_1 passes the other half, but the energy of this other half is wasted in the output of repeater R and the impedance looking into the input end of filter F'_1 , since the repeater is a unilateral current transmitting element and the filter F'_1 is designed to suppress this other half of the voice frequencies. The frequencies passed by filter F_1 are amplified by the repeater and passed through filter F'_1 to line E . The filter F_2 , like the filter F'_2 , will not pass these frequencies. The impedances looking into the input end of filter F'_2 , the output end of filter F_2 , the output end of filter F'_2 and the input end of filter F_2 should be designed, as for instance in a way indicated hereinafter, to be high for these frequencies to avoid large losses at these frequencies. The operation of transmitting from line E to line W is of course the same as that described for transmission East, except that the transmission is through filters F_2 and F'_2 instead of through filters F_1 and F'_1 , and the filters F_2 and F'_2 pass only those frequencies which are not passed by filters F_1 and F'_1 .

In Fig. 4 a line L serves for duplex transmission of voice currents between lines L_1W and L_1E and at the same time for duplex transmission of voice currents between lines L_2E and L_2W . In order to accomplish this result, filters AF_1 , AF'_1 , AF_2 and AF'_2 are inserted in lines L_1W , L_1E , L_2E and L_2W , respectively, these filters being similar to the correspondingly designated filters F_1 , F'_1 , F_2 and F'_2 , respectively, of Fig. 3, but having their terminal reactance elements at those ends of the filters which are the more remote from line L consisting of a series arm the impedance of which is, as usual, half the impedance of a full series arm.

In the operation of this system, when a voice current containing all of the usual voice frequencies originates in line L_1W approximately one half of these frequencies is suppressed by filter AF_1 . The other half is transmitted through filter AF_1 , line L and filter AF'_1 to line L_1E . Filters AF'_2 and AF_2 exclude the latter frequencies from lines L_2W and L_2E respectively. The impedances looking into the output end of filter AF'_2 and the input end of filter AF_2 should be high for these frequencies to avoid large losses at these frequencies. The frequencies which filters AF'_1 and AF_1 are designed to pass are of course also excluded from lines L_2E and L_2W by the filters AF_2 and AF'_2 , respectively, when these frequencies are being transmitted from line L_1E through filter AF'_1 , line L and filter AF_1 to line L_1W .

When a voice current containing all of the usual voice frequencies originates in line L_2W approximately one half of these

frequencies is suppressed by filter AF'_2 . The other half is transmitted through filter AF'_2 , line L and filter AF_2 to line L_2E . Filters AF_1 and AF'_1 exclude the latter frequencies from line L_1W and L_1E , respectively. The impedances looking into the output ends of filters AF_1 and AF'_1 should be high for these frequencies to avoid large losses at these frequencies. The frequencies which filters AF_2 and AF'_2 are designed to pass are of course also excluded from lines L_1E and L_1W by the filters AF'_1 and AF_1 , respectively, when these frequencies are being transmitted from line L_2E through filter AF_2 , line L and filter AF'_2 to line L_2W .

It will be clear that in a system such as that shown in Fig. 4 the impedances looking into the East ends of the filters AF_1 and AF'_1 may be connected in series with each other, instead of in parallel, just as the impedances looking into the West ends of filters 1 and 4 of Fig. 2 are connected in series and the impedances looking into the East ends of these latter filters are connected in series instead of the impedances looking into their West ends being connected in parallel and the impedances looking into their East ends being connected in parallel as are the corresponding impedances of filters AF_2 and AF'_2 in Fig. 3. The filters AF_2 and AF'_2 in Fig. 4 may have the impedances looking into their West ends connected either in series or in parallel, regardless of whether the filters AF_2 and AF'_2 have the impedances looking into their West ends connected in parallel or in series.

The impedance looking into the input of filter FW of Fig. 1 may be made low for the frequencies passed by filter FE and the impedance looking into the input of filter FE be made low for the frequencies passed by filter FW , by properly terminating these filters at their input ends. For instance, if FE be a low pass filter suppressing all frequencies above 1500 and FW be a high pass filter suppressing all frequencies below 1500, then assuming each of these filters to be made up of, for instance, a plurality of sections each section of filter FE consisting, say, of a series inductance element and a shunt capacity element after the fashion of the filter of Fig. 7 of U. S. Patent to G. A. Campbell, 1,227,113, May 22, 1917, entitled Electrical receiving translating, or repeating circuit, and each section of filter FW consisting, say, of a series capacity element and a shunt inductance element after the fashion of the filter of Fig. 6 of the Campbell patent mentioned above, then the first section of high pass filter FW may be made to begin with a shunt inductance element having an impedance which is low for the frequencies passed by low pass filter FE , and the first section of low pass filter FE

may be made to begin with a shunt condenser having a low impedance for the frequencies passed by high pass filter FW.

Similarly, assuming the filters 1 and 2 of Fig. 2 to be, for instance, low pass filters like that of Fig. 7 of the Campbell patent mentioned above, and filters 3 and 4 to then be high pass filters such as that of Fig. 6 of the Campbell patent, then each end of high pass filters 3 and 4 may be terminated in a shunt inductance element of low impedance for the frequencies passed by low pass filters 1 and 2, and each end of low pass filters 1 and 2 may be terminated in a shunt condenser of low impedance for the frequencies passed by high pass filters 3 and 4.

It will be clear that when one end of a low pass filter is connected in parallel with one end of a high pass filter, as for instance in providing a system such as is shown in Figs. 3 and 4, then the one end of the high pass filter may be made to begin with a series condenser having high impedance for the frequencies passed by the low pass filter, and the one end of the low pass filter may be made to begin with a series inductance element having high impedance for the frequencies passed by the high pass filter.

Preferably where it is desired to connect a high pass filter such as is shown in Fig. 6 of the Campbell patent referred to above in parallel with a low pass filter such as is shown in Fig. 7 of that patent, for separating currents into two channels, the filters should have approximately the same cut-off frequency and, using the symbols employed in the patent, Z_1, Z_2 should be constant with varying frequency and $\frac{L_2}{C_1}$ should be equal

to $\frac{L_1}{C_2}$. Then the first filter should be terminated with a series condenser having a value of approximately $1.25 C_1$ at the end which is to be connected in parallel with the second filter and the second filter at the corresponding end should be terminated in a series reactance coil having an inductance of $.8 L_1$. If the ends of the filters are to be connected in series the first filter should end in a shunt element having an inductance of $1.25 L_1$ and the second should end in a shunt element having a capacity of $.8 C_2$. If this is done the impedances of the filters will be such that the combination will have a practically constant impedance at all frequencies except in the immediate vicinity of the cut-off frequency and neither filter will interfere deleteriously with the operation of the other.

The principles and reasons underlying this design of the filters are set forth in detail in the United States Patent to Otto J. Zobel, No. 1,557,230, dated October 13, 1925, entitled "Complementary filters", issued on application Serial No. 377,965, filed April 30, 1920.

In a similar way when a multi-band filter is to be used instead of the high or low pass filter, in accordance with the principles set forth in the Zobel application referred to above the impedance of the series arm multiplied by the impedance of the shunt arm should preferably be constant at all frequencies and the filter should preferably be terminated in a series section having approximately .8 times the impedance of the full series section if it is to be connected in parallel with a complementary filter, or in a shunt section having approximately 1.25 times the impedance of the full shunt section if it is to be connected in series with a complementary filter. A method of designing a wave filter in which the impedance of the series arm multiplied by the impedance of the shunt arm is constant with varying frequency, and which will transmit over any preassigned number of frequency ranges is disclosed in United States Patent to Zobel, No. 1,509,184, dated September 23, 1924, entitled "Multiple band wave filter", issued on application Serial No. 377,963, filed April 30, 1920.

As noted above, a part of the filter in each channel in Fig. 1 can be placed at each side of the amplifier in that channel, after the general fashion in which the filtering means 1 and 2 in Fig. 2 is placed partly at each side of the amplifier R. Then the resultant of the impedances looking from line W into the two channels, and the resultant of the impedances looking from the line E into the two channels may be made practically constant at all frequencies except in the immediate vicinity of the cut-off frequencies, in the manner explained above.

What is claimed is:

1. The method of treating a number of telephonic messages simultaneously impressed upon the line, each as a group of alternating currents in the voice frequency range, which comprises separating at the receiving end of the line groups of currents each of which groups represents one of said messages, and one of which groups consists of currents of frequencies lying outside the limits of the frequencies of the currents in another of said groups.

2. The method of operating a repeater having oppositely directed unilaterally repeating paths which comprises transmitting in one of said paths voice currents of frequencies limited to part of the voice frequency range, and transmitting in the other of said paths voice currents of frequencies limited to the remainder of the voice frequency range.

3. A system for repeating voice frequency currents, comprising a line and a two-way repeater circuit including transmission paths, selective of voice currents of certain frequencies, for frequency separation of op-

- positively directed voice frequency currents transmitted over both of said lines in the opposite direction, an amplifier for all of said waves, an input circuit and an output circuit each having two branches one for each line, and filters in each of said branches. 70
4. In a voice frequency telephone system, the combination with two line circuits for transmitting voice currents, of a two channel connecting circuit for transmitting voice frequencies in opposite directions, said two channels having a common transmitting portion and being simultaneously in condition to transmit between said two lines. 75
5. In a voice frequency telephone system, the combination with two line circuits for transmitting voice currents, of a two channel connecting circuit for transmitting voice frequencies in opposite directions, said two channels having a common unilaterally transmitting portion normally connected for transmission in each direction between said line circuits. 80
6. A line for transmitting a plurality of voice current waves of substantially different voice frequencies in each direction, a second similar line, and two-way repeating means capable of repeating said waves simultaneously without mutual interference between said lines, said means comprising a single amplifying path associated with both of said lines. 85
7. Two lines for transmitting voice frequency currents in both directions, and an amplifier having an input circuit coupled to both of said lines, and an output circuit coupled to one of said lines through a path selective of certain voice frequencies and to the other line through a path selective of only other voice frequencies. 90
8. Two lines for the transmission of voice frequency currents in both directions, a one-way selective path between said lines for transmitting voice frequency currents having certain characteristics, another one-way selective path between said lines for transmitting in the opposite direction only voice frequency currents of characteristics different from the first mentioned characteristics, and a single amplifier common to both said paths. 95
9. Two lines for the transmission of voice frequency currents in each direction thereover, the voice currents transmitted through both of said lines in one direction having different characteristics from those transmitted through both of said lines in the opposite direction, an amplifier for amplifying all of said currents having its input and its output circuits each common to both of said lines, and a plurality of selective paths in said output circuit between said amplifier and each of said lines for selectively transmitting said currents. 100
10. Two lines for the transmission of voice current waves in each direction thereover the voice current waves transmitted over both of said lines in one direction having respectively different characteristics from those
- transmitted over both of said lines in the opposite direction, an amplifier for all of said waves, an input circuit and an output circuit each having two branches one for each line, and filters in each of said branches. 70
11. A line, a two-way repeater in said line comprising a circuit for transmission of voice frequency currents in one direction, and another circuit for transmission of currents of other different voice frequencies in the opposite direction, an amplifier in one of said circuits, another amplifier in said other circuit, and selective means in one of said circuits for selecting the frequencies used in transmitting in one direction, and selective means in the other circuit for selecting the frequencies used in transmitting in the opposite direction. 75
12. In a telephone system, transmission line sections, one-way transmission paths interconnecting said line sections, and selective means whereby only a portion of the voice frequencies approaching said paths from one direction over said line sections will pass over one of said paths, and whereby of the voice frequencies approaching said paths from the opposite direction only frequencies different from those passed by said one path will pass over the other of said paths. 80
13. In a telephone system, transmission line sections, one-way transmission paths interconnecting said line sections, one-way repeaters in each of said paths and selective means in one of said paths whereby only a portion of the voice frequencies approaching said paths over said line sections in one direction will pass over said one path, and selective means in the other path whereby of the voice frequencies approaching said paths over said line sections in the opposite direction only frequencies different from those passed by said one path will pass over said other path. 85
14. A channel comprising a band filter for transmitting voice frequencies lying between certain limits, a second channel comprising a second band filter for suppressing frequencies between said limits, each filter being capable of passing voice currents representing intelligible speech, and a line having one end connected to one end of the first mentioned channel and to one end of said second channel, the impedance of said second channel looking from said end of said line and said end of said first channel being of such value for the frequencies passed by said first channel that the volume loss in transmission due to said impedance is small for frequencies transmitted through said line and said first filter. 90
15. A common transmission path, a plurality of channels each adapted to transmit currents of different frequency from those transmitted by the other channels, and a 100

separate band filter transmitting voice frequencies connecting each channel to said path, the terminations of said filters electrically adjacent said path being connected 5 in parallel.

16. A common transmission path, a plurality of channels each adapted to transmit currents of different frequency from those transmitted by the other channels, and a 10 separate band filter capable of passing voice currents representing intelligible speech connecting each channel to said path, the terminations of said filters electrically adjacent said path being connected in parallel.

15. 17. A circuit, a plurality of voice current channels associated therewith, means for transferring voice currents of different voice frequencies between said channels and said circuit, said means comprising an individual 20 filter connected to each of said channels, the transmission range of each filter being distinct and being such as to permit passage of voice currents representing intelligible speech, said filters having terminations connected in parallel to said circuit, the termination 25 of each filter having a high impedance for currents of the transmission frequency range of any other filter whereby said filters do not short-circuit each other.

30 18. A common transmission path, two voice current channels associated therewith,

one of said channels adapted to be traversed by voice currents lying within a given voice frequency range, the other of said channels being adapted to be traversed by a voice 25 current of a different range of voice frequencies, a filter capable of passing voice currents representing intelligible speech connecting the first of said channels to said path and a second filter capable of passing voice 40 currents representing intelligible speech connecting the second of said channels to said path, each of said filters comprising sections having shunt and series arms, each filter being terminated in a series arm having approximately .8 times the impedance of a full series arm, and the terminations of said filters being connected to said path in parallel. 45

19. The method of two-way telephone transmission of speech currents over the same 50 line comprising transmitting in one direction over said line currents in the ordinary speech frequency range confined to frequencies higher than a given limiting frequency, and transmitting in the opposite direction over 55 said line currents in the ordinary speech frequency range confined to frequencies lower than said given limiting frequency.

In witness whereof, I hereunto subscribe my name this 24th day of September A. D., 60 1921.

FREDERICK WHITTLESEY McKOWN.
